E. T. RICHEY

AUTOMATIC TELEPHONE RINGER

Filed May 27, 1924

Patented Feb. 2, 1926.

1,571,435

UNITED STATES PATENT OFFICE.

ELDRED THURSTON RICHEY, OF LE BLANC, LOUISIANA.

AUTOMATIC TELEPHONE RINGER.

Application filed May 27, 1924. Serial No. 716,133.

To all whom it may concern:

Be it known that I, ELDRED THURSTON RICHEY, a citizen of the United States, residing at Le Blanc, in the parish of Allen 5 and State of Louisiana, have invented certain new and useful Improvements in an Automatic Telephone Ringer, of which the following is a specification.

This invention relates to automatic telephone ringers especially adapted to be used in conjunction with telephone switch boards and it consists in novel features hereinafter described and claimed.

An object of the invention is to provide 15 an instrument or apparatus in which a circuit may be closed and a switch may be positioned whereby a desired number of rings may be sounded in the call station eliminating the necessity of turning a crank a certain definite number of times in order to produce the ring call.

In the accompanying drawing:

Figure 1 is a diagrammatic view of the 20 automatic telephone ringer.

Figure 2 is a transverse sectional view thereof cut on the line 2—2 of Figure 1.

Figure 3 is a side elevation of a disk used in the apparatus.

Figure 4 is an edge elevation of the disk.

Figure 5 is a side elevation of another disk used in the apparatus.

The automatic telephone ringer comprises a base 1 having a series of electromagnets 2 mounted thereon. Spring contacts 3 are 25 mounted upon the base 1 opposite the cores of the magnets 2. A contact member 4 is mounted upon the base 1. A motor 5 is mounted upon the base 1 and a disk 6 is mounted upon the shaft of the motor 5. A 30 contact 7 is mounted upon the base 1 and bears against the disk 6. A binding post 8 is mounted upon the contact 7. A set screw 10 is carried by an extension 9 of the base and bears upon the shaft of the motor 5 and 35 serves to regulate the rate of speed at which the said shaft may rotate. A series of metal terminals 11 is mounted upon the magnets 2. A crank 12 is provided upon the shaft of the motor 5. A rod 13 is connected with the 40 crank 12 and carries a metal strip 14 which is mounted in guides 15. The guides 15 are mounted upon a magnet 16 which in turn is mounted upon the base 1 and the plate 14 is normally held spaced from the core of the magnet 16. The shaft of the motor 5 is indicated at 17. A series of disks 18 is 45

mounted upon the shaft 17. The disks 18 are insulated from each other as at 19. Binding screws 20 are mounted upon the base 1 opposite the disks 18. Each disk 18 is provided upon its periphery with a strip 21 of insulating material. Contacts 22 are connected with the binding post 20 hereinbefore mentioned. The numbers shown at 23 indicate the number of call rings which are to be produced at the telephone, for instance the number two and one-half signifies that the call rings are to be two long rings and one short ring. Contact points 24 are located adjacent the numbers 23. A 28 push button 25 is mounted adjacent the row of contact points 24. A switch lever and knob 26 is mounted opposite the push button 25, in which the switch lever may be set on any desired contact point 24 by turning the knob. Wires 27 (see Figure 3) are carried by each disk 18 connected to a copper lined groove provided upon the disk. The groove is indicated at 28. Brass plates 29 are mounted upon the disk 18 and connected with the wires 27. The said plates 29 are also adapted to have contact with the flexible contact members 3 as the disks 18 rotate. The relatively long plates upon the disks 18 produce a long call ring and a 33 short plate produces a short call ring. The spaces 30 between the ends of the adjacent plates 29 upon the disks 18 produce the interruption in the ring which is produced at the telephone. The disk 6 carries a wire 31 which contacts with a relatively long plate 32 mounted upon the periphery of the said disk. The contact 4 engages the plate 32. The contact 7 engages in a copper lined groove 33 provided in the disk 6. The wire 31 carried by the disk 6 makes a connection with both the plate 32 and the copper lined groove 33. At 34 a gap is shown between the ends of the plate 32 (see Figure 5). A wire 35 connects the push button 25 with the magnet 16. The wire 36 connects the push button 25 with a battery 37 and with a telephone instrument 38. Wiring 39 connects the magnet 16 with the battery 37, with the motor 5 and with the switch lever 26. Wiring 40 connects the contact point 24 with the magnet 2.

When the push button 25 is closed, a circuit is completed from the battery 37 to the magnet 16 whereby the bar 14 is attracted 40 and the rod 13 is moved thus giving the crank 12 and the shaft 17 a slight turn,

which is enough to turn the disk 6 so that the plate 32 is brought in contact with the contact member 4. Thus the gap 34 is moved from under the contact 4 and an electric circuit is completed to the motor 5 from the battery 37 which turns the shaft 17 at a slow rate of speed. At the time that the push button 25 is closed the switch lever 26 is set on the desired contact point 24 and 10 thus when the plate 32 comes in contact with contact member 4 a circuit is completed from the battery 37 to one of the magnets 2. The magnet switch is thus energized and attracts the flexible contact 3 and draws the same into engagement with the adjacent terminal 11 which completes a circuit to the telephone instrument 38. The disk 6 furnishes the current for the motor with the plate 32 contacting with the 20 contact member 4 and the contact 7. The magnet 16 turns the disk until the plate on it comes in contact with the member 4. The contact member 7 is at all times in engagement with the disk 6. When the motor 25 starts the disk 18 which is opposite the energized magnet, it revolves and the plates 29 come in contact with the contact members 3, thus completing the circuit through the terminal 11 and terminal 22 and thus the 30 rings are sounded at the telephone. After the first plate upon the disk has passed, the

gap 30 comes opposite the magnet and the circuit is broken, thus the ring at the telephone is interrupted. When the disk 6 completes a rotation, the contact member 4 seats in the gap 34 and thus the supply of current from the battery to the motor is interrupted and the motor comes to a state of rest.

Having thus described the invention, what I claim is:—

An automatic telephone ringer comprising a motor, a disk mounted upon the shaft of the motor, a plate mounted upon the periphery of the disk, contact members engaging said plate, a battery connected with the contact members and the motor, a telephone connected with the battery, a selective switch device connected with the battery, disks mounted upon the shaft of the motor and having spaced plates, contacts adapted to engage the last mentioned disks, a magnet for moving one of the last mentioned contacts and electrically connected with the point switch mechanism, a terminal located in the path of movement of said contact and electrically connected with the telephone instrument, and a magnet operatively connected with the shaft of the motor and electrically connected with a push button and the battery.

In testimony whereof I affix my signature.

E. THURSTON RICHEY.
